SPOOL

Marius Gazet, Lyon, France, assignor to Etablissements G. Decombe, Lyon, a company of France

Application November 28, 1950, Serial No. 197,855
In France December 21, 1949

8 Claims. (Cl. 242—129)

1

When it is desired to coil wires, chiefly electric conductors, into annular formation, they are wound over a spool provided with a removable flange and the drum portion of which is either conical or expandable in order to provide for the easy removal of the annulus formed by the coiling of the wire.

In order to prevent such coiled annuli from collapsing, it is necessary as soon as the wire is wound to secure it to the actual head of the coiling machine by means of three or four strings or ribbons; now the duration of this attaching step corresponds to about 30 or 40% of the time required for the coiling step; this leads to a considerable reduction in the normal production that may be yielded by the machine.

To remove this drawback, it has been proposed to build a coiling machine with two heads of which, at a given moment, one serves for the winding of a wire annulus while the other is stationary to allow the attaching of the finished annulus on it; the yield of the machine is then satisfactory, but its cost price is a high one by reason of the actual complication of the mechanism controlling the alternately operating control systems of the two heads.

My invention has for its object to remove these drawbacks and it relates to a head for a machine adapted, whether singly or otherwise, to coil into annuli wires, ropes, cables or the like, and to attach the formed annulus outside the said machine so as to obtain an improved yield for said machine although it includes only a single head.

To this end, the spool on the head of the coiling machine, considered is provided, on the inner surface of its flange and on the outer peripheral surface of its drum, with grooves wherein are fitted the rods constituting respectively the flange and the drum of a carcass or skeleton forming an auxiliary spool, said skeleton serving for the removal of the annulus as soon as it has been formed and also for the keeping of the latter in the shape given to it when it is removed off the machine until the convolutions forming it are suitably attached.

According to a preferred embodiment, the skeleton forming an auxiliary spool is constituted by a circular ring made of a tubular or a solid, round or shaped, iron member to which ring are secured inwardly directed radial arms, the ends of which

2

are bent at right angles and form the framework of the drum of said auxiliary spool.

My invention will be readily understood furthermore through the reading of the following description, reference being made to accompanying diagrammatic drawings given by way of example and by no means in a binding sense, said description and drawings relating to a preferred embodiment of the invention. In said drawings:

Fig. 1 is a perspective view of the skeleton forming the auxiliary spool;

Fig. 2 is a view from above of the same skeleton carrying an annulus of wire attached thereto;

Figs. 3 and 4 are respectively a cross-sectional view through line 3—3 of Fig. 4 and a view from above of a spool provided with such an auxiliary spool, said views illustrating the actual winding of the wire annulus;

Figs. 5 and 6 are similar views of the same arrangement illustrating the removal of the auxiliary spool and of the annulus carried thereby after the latter has been coiled into annular shape;

Fig. 7 is an axial sectional view of a modified embodiment of a spool including two auxiliary spools or skeletons;

Fig. 8 is a partial view, on an enlarged scale, including an axial cross-section of a modification wherein the arms of the associated skeletons interengage one another telescopically.

The auxiliary spool illustrated in Figs. 1 and 2 is constituted by a skeleton including a metal ring 2 to which are secured four inwardly directed radial arms 3 the ends 4 of which are bent at right angles in a direction perpendicular to the plane of the ring so as to form a sort of drum while the ring 2 and the radial parts of the arms 3 form a sort of flange.

On the other hand, the actual spool 5 carries at the inner face of its flange 6, radial grooves 7 (Fig. 4) inside which are housed the radial arms 3 of the auxiliary spool and it carries on the outer surface of its expandible drum 8 (Fig. 5) longitudinal grooves 9 adapted to house the raised ends 4 of the arms 3 of the skeleton spool. When the drum 8 of the spool 5 is in its expanded condition as illustrated in Figs. 3 and 4, the auxiliary spool is entirely enclosed inside the main spool 5 and consequently does not interfere in the coiling operation.

As soon as the coiling is at an end, the rotation of the spool 5 is at an end and it is sufficient to connect the end of the wire 10 that is being coiled to the nearest radial arm 3 in order to prevent any unwinding of the wire and the consequent collapse of the annulus formed, chiefly if the wire is a steel or the like wire showing a certain resilience.

The drum 8 of the spool 5 is then caused to shrink as illustrated in Figs. 5 and 6; the wire annulus 10 is thus held only through the skeleton 4 of the drum of the auxiliary spool. The system including the wire annulus 10 and the auxiliary spool may thus be removed without any effort being required and without the annulus 10 collapsing; the attaching of said annulus is performed subsequently outside the machine when the latter has already been started again after positioning on the spool 5 of a further auxiliary spool similar to the one referred to precedingly.

The two said auxiliary spools per machine head provide for the positioning of one of them on the machine, for the actual formation of the annulus while the other auxiliary spool serves for the final attaching of the convolutions of the coiled wire.

It should be remarked that in the embodiment disclosed, the second removable flange 12 of the spool 5 is of the conventional type as fully apparent from Figs. 3 and 5. In a modification, it may carry a skeleton as shown in Figs. 7 and 8, similar to the first skeleton associated with the removable flange 6. The radial arms 3a of this second skeleton are bent at their ends 4a so as to register with the inturned ends of the arms of the first skeleton, as shown in Fig. 7, or else, they are fitted inside them telescopically as shown in Fig. 8.

Obviously, the number of radial arms in the auxiliary spool or spools may be selected as desired.

Obviously, moreover, my invention is by no means limited to the single embodiment disclosed by way of example and it includes all the modifications falling within the scope of appended claims.

What I claim is:

1. A coil carrier comprising a drum and two flanges one of which at least is removable, a skeleton spool including a plurality of convergent interconnected arms bent inwardly at right angles at equal distances from the point of convergence of said arms, the inner bent parts of said arms bearing against the periphery of the drum, said skeleton spool being adapted to carry, independently of the drum and flanges, a wire coiled round the bent parts of the arms with the end surface of the coiled wire bearing against the outer convergent parts of said arms.

2. A coil carrier comprising a radially expandable drum and two flanges one of which at least is removable, a skeleton spool including a plurality of convergent interconnected arms bent inwardly at right angles at equal distances from the point of convergence of said arms, the inner bent parts of said arms bearing against the periphery of the drum, said skeleton spool being adapted to carry, independently of the drum and flanges, a wire coiled round the bent parts of the arms with the end surface of the coiled wire bearing against the outer convergent parts of said arms.

3. A coil carrier comprising a drum having a tapering periphery and two flanges one of which at least is removable, a skeleton spool including a plurality of convergent interconnected arms bent inwardly at right angles at equal distances from

the point of convergence of said arms, the inner bent parts of said arms bearing against the periphery of the drum, said skeleton spool being adapted to carry, independently of the drum and flanges a wire coiled round the bent parts of the arms with the end surface of the coiled wire bearing against the outer convergent parts of said arms.

4. A coil carrier comprising a drum provided on its outer periphery with at least two longitudinal grooves parallel with its axis, flanges coaxial with the drum of which one is provided with radial grooves facing the drum, at least one flange being removably secured to the drum, a skeleton spool including a plurality of convergent interconnected arms bent inwardly at right angles at points at equal distances from the point of convergence of said arms, the convergent outer portions of said arms engaging releasably the radial grooves in the flange and the inner bent ends of the arms engaging releasably the peripheral longitudinal grooves of the drum, said skeleton being adapted to carry independently of the flanges and drum a coiled wire round the bent parts of the arms with one side of the coil bearing against the outer convergent parts of said arms.

5. A coil carrier comprising an inwardly collapsible drum provided on its outer periphery with at least one longitudinal groove parallel with its axis, flanges coaxial with the drum of which one is provided with radial grooves facing the drum, at least one flange being removably secured to the drum, a skeleton spool including a plurality of convergent interconnected arms bent inwardly at right angles at points at equal distances from the point of convergence of said arms, the convergent outer portions of said arms engaging releasably the radial grooves in the flange and the inner bent ends of the arms engaging releasably the peripheral longitudinal grooves of the drum, said skeleton being adapted to carry independently of the flange and drum a coiled wire round the bent parts of the arms with one side of the coil bearing against the outer convergent parts of said arms.

6. A coil carrier comprising a drum provided on its outer periphery with at least one longitudinal groove parallel with its axis, flanges coaxial with the drum of which one is provided with radial grooves facing the drum, a skeleton spool including a metal ring, the radius of which is larger than that of the drum and of the flanges and convergent arms radially secured inside said ring and the inner ends of which are bent at right angles at points at equal distances from the center of the ring, the convergent outer portions of said arms engaging releasably the radial grooves in the flange and the inner bent ends of the arms engaging releasably the peripheral longitudinal grooves of the drum, said skeleton being adapted to carry independently of the flange and drum a coiled wire round the bent parts of the arms with one side of the coil bearing against the outer convergent parts of said arms.

7. A coil carrier comprising a drum and two flanges one of which at least is removable, two skeleton spools including a plurality of convergent interconnected arms bent inwardly at right angles at points at equal distances from the point of convergence of said arms, the inner bent arm parts of each skeleton spool being directed towards the other skeleton spool and bearing against the periphery of the drum, said skeleton spools being adapted to carry, independently of the drum and flanges, a wire coiled round the

bent parts of the arms with the end surfaces of the coiled wire bearing against the outer convergent parts of said skeleton spool arms.

8. In combination with a carrier drum, the provision of at least one independent skeleton spool adapted to be removably fitted over said drum and to carry a coiled wire, said skeleton spool comprising a plurality of convergent interconnected arms and extensions of said arms bent inwardly at right angles at points at equal distances from the point of convergence of said arms and adapted to engage the periphery of the drum.

MARIUS GAZET.
